[57] CLAIM

The ornamental design for a fascia gutter, as shown and described.

DESCRIPTION

FIG. 1 is a top plan view of a fascia gutter showing my new design, the fascia gutter being broken in the center to indicate indeterminate length;

FIG. 2 is a left-end elevational view thereof;

FIG. 3 is a right-end elevational view thereof;

FIG. 4 is a bottom plan view thereof; and,

FIG. 5 is a fragmentary perspective view thereof.

FIG.1
